[57] CLAIM

The ornamental design for a wall mounted flower holder unit, as shown.

DESCRIPTION

FIG. 1 is a top plan view of wall mounted flower holder unit showing my new design;

FIG. 2 is a front elevational view of FIG. 1;

FIG. 3 is a bottom plan view of FIG. 1;

FIG. 4 is a side elevational view taken from the right of FIG. 2 the side opposite being a mirror image thereof;
FIG. 5 is a top plan view of a second embodiment of the design of FIG. 1;

FIG. 6 is a front elevation view of FIG. 5;

FIG. 7 is a bottom plan view of FIG. 5;

FIG. 8 is a side elevational view taken from the right of FIG. 6, the side opposite being a mirror image thereof.
